RUG CLEANING NOZZLE

Kemper M. Hammell, Detroit, Mich., assignor to
Eureka Williams Corporation, a corporation of
Michigan

Application April 3, 1944, Serial No. 529,358

6 Claims. (Cl. 15—368)

1

This invention relates to suction cleaners and has particular reference to a rug nozzle provided with a traction driven brush and adapted in the embodiment of the invention selected for purposes of illustration to be connected with a source of suction, such as that provided by a vacuum cleaner. Certain features of the invention may be utilized in other forms of the device than the particular type illustrated.

Principal objects of the invention are to provide:

A new and improved suction cleaner;
A new and improved rug nozzle for a suction cleaner;

A new and improved rug nozzle provided with a rotary brush;

A new and improved rug nozzle having a handle for maneuvering the same and provided with means for taking the handle thrust so that the nozzle will tend to ride on the top of the nap of the carpet;

A rug cleaning suction tool provided with a rotary brush and a handle for maneuvering the tool, with the nozzle and brush of the tool constructed and arranged to ride on the top of the nap of the carpet being cleaned.

Other objects and advantages of the invention will be apparent from a consideration of the following specification taken in conjunction with the accompanying drawings of which there are two sheets and wherein:

Fig. 1 is a plan view of a device embodying the invention;

Fig. 2 is an enlarged fragmentary rear elevational view with certain parts thereof broken away;

Fig. 3 is a cross sectional view taken along the line 3—3 of Fig. 2, looking in the direction of the arrows;

Fig. 4 is a fragmentary sectional view taken along the staggered line 4—4 of Fig. 3, looking in the direction of the arrows, and illustrating the driving means for the rotary brush;

Figs. 5 and 6 are sectional views taken along the lines 5—5 and 6—6 respectively of Fig. 2;

Fig. 7 is a reduced view of the rug nozzle with a handle connected thereto; and

Fig. 8 is an enlarged fragmentary view of the driving connection between one of the wheels and the rotary brush.

In the embodiment of the invention selected for purposes of illustration there is provided a suction cleaning tool which might be termed a rug or carpet cleaning nozzle. This nozzle comprises a casing 10 formed by a base 12 and a hood or cap 14. A socket 16 formed in one end of a

2

coupling member 17 which projects rearwardly and upwardly from the casing 10 is adapted for receiving the end of a pipe or wand 18 which forms a handle by means of which the rug nozzle 5 may be maneuvered over a rug or carpet for cleaning the same.

The pipe or wand 18 may have any suitable detachable connection with the socket 16 and the upper end of such pipe or wand may be adapted to receive the end of a hose which is connected with a suitable source of suction, such as that provided by a conventional suction cleaner of the tank type.

The coupling member 17 communicates with the interior of the casing 10 and may comprise a tubular member, one end 20 of which is fitted into a suitable opening provided in the connecting part of a U-shaped bracket or bail 22. Each arm 24 of the bail has affixed thereto and projecting outwardly therefrom a stub shaft 26, the said stub shafts 26 being arranged in axial alignment. The inner ends 28 of the stub shafts 26 may be formed with a rivet head so as to rigidly secure the shafts 26 to the arms of the bail 22. Each shaft 26 has journaled thereon a wheel 30 which may include a tire 32 made of rubber or the like. The wheels 30 are arranged between the arms 24 of the bail and the inside ends of the casing 10, the base 12 being provided with slots 34 through which the bottoms of the wheels 30 may extend so as to roll upon the carpet or other surface over which the rug nozzle may be maneuvered.

Each of the stub shafts 26 at their outer ends 35 are provided with a reduced portion 36 forming a guide for cooperation with a guide 38 provided by a vertically extending slot or groove formed in the inside of the adjacent end wall 40 of the casing 10. The guides 38 cooperating with the guides 36 prevent the wheels 30 from shifting laterally relative to the casing 10 while permitting free and unrestricted vertical shifting within limits of the wheels 30 relative to the casing 10. The guide slots 38 are of such length that the bottom 40 of the wheels 30 may project through the slots 34 and below the base 12 at least three-eighths of an inch when the wheels 30 are in their lowermost position relative to the casing 10. Due to the manner in which the handle 18 is mounted 45 upon the wheels 30, the latter take all of the thrust of the handle when the rug nozzle is being maneuvered over a carpet.

The base 12 of the nozzle may be provided with 50 suitably formed surfaces such as sleds or runners 42. These runners extend parallel to the direction that the nozzle is adapted to be moved over

a carpet and may be provided one at each end of the nozzle on the underside thereof and just inside the wheels 30. The surfaces provided by the sleds or runners 42 are adapted to ride upon the nap of the carpet or rug with but very little sinkage since the wheels 30 take the handle thrust. The sinkage will depend to some extent on the character of the rug. The lower surface of face of the base 12 slopes upwardly and inwardly from the runners 42 so that the lower surface of the base between the runners is arranged at a slightly higher elevation than the surfaces of the runners 42. This is done to reduce the frictional drag between the base 12 and the carpet and also to insure that the mouth 44 of the nozzle will be positioned substantially in the plane of the top surface of the nap of the carpet as the runners 42 will sink into the surface of the carpet a slight amount under the weight of the mass of the nozzle and the torque reaction of the driving connection between the wheels 30 and the rotary brush 60 when the nozzle is being pushed forwardly.

The base 12 may, as illustrated, be provided by a stamping which is formed to provide the mouth 44 of the nozzle and the runners 42. The nozzle mouth 44 extends parallel to the forward side of the rug nozzle and substantially from end to end thereof. The stamping which provides the base 12 may be provided with a peripheral upstanding flange 46 which is snugly fitted within a complementary shaped marginal flange 48 formed around the lower end of the hood 14. The hood 14 may be provided by a molded plastic of the types now commonly used for parts of this kind. A bumper 50 of resilient material may encircle the casing 10 at the joint between the base 12 and the hood 14.

The coupling member 17 projects through an opening in the hood 14 which permits the handle 18 of which the coupling member 17 forms a part to pivot on the shafts 26 throughout a substantial arc; that is, from almost a vertical position to approximately a horizontal position. Each side of the opening in the hood 14 through which the coupling member 17 projects is provided with a curved groove or track 52. A curved member 54 is slidable in the grooves or tracks 52. The member 54 is provided with a hole through which the neck 56 of the coupling member 17 extends, the edges of the hole having a close fit with the neck 56 so as substantially to seal the same while permitting a sliding movement of the coupling member axially with respect to the hole through the member 54. This movement occurs when the wheels 30 move vertically relative to the casing 10. The member 54 and the tracks 52 are adapted to provide a seal between the coupling member and the hood so as to permit a limited pivotal or axial movement of the coupling member with respect to the hood 14 and nozzle of which the hood is a part.

A rotary brush indicated generally at 60 is rotatably mounted within the nozzle just above the mouth 44 thereof and so that the ends of the bristles 62 of the brush will be positioned substantially in the plane of the mouth of the nozzle. The rotary brush 60 includes a pair of axially aligned rotary bodies 64 having bristles or equivalent devices suitably provided thereon. Each of the rotary bodies 64 at its outer end (that is, at the end thereof adjacent the wheel 30) is provided with a stub shaft 66 projecting therefrom at the axis thereof. The stub shafts 66 are rotatably supported by a self-aligning bearing 68.

and the outer end of the shaft 66 has affixed thereto a pinion 70 the teeth of which mesh with the teeth of an internal gear 72 formed or provided internally on the wheel 30. At the inner or adjacent ends of the rotary bodies 64 a sleeve bearing 74 is arranged at the axis of each of the rotary bodies 64. A shaft 76 extends into and between said bearings 74 so as to align the same and to permit rotation of one relative to the other. The shaft 76 between the adjacent ends of the rotary bodies 64 is supported by an arm 78 of a bracket 80 which additionally includes arms 82 parallel to the arm 78 but arranged adjacent the bearings 68. The bracket 80 including the arms 78 and 82 thereof thus supports the two aligned sections 64 of the rotary brush for movement about the same axis. The arms 82 may be spaced from the outer ends of the sections 64 of the rotary brush by suitable gaskets 84.

Each of the bearings 68, which may be of the self-aligning type formed of an oil-impregnated material, is suitably mounted in a circular wall or plate 86 which has a running fit within the rim of the wheel 30. The wall 86 is rotatably mounted on a part of the stub shaft 26 between the arm 24 of the bail 22 and the hub of the wheel 30. The wall 86 includes inner and outer parallel members 88 and 90 spaced at their periphery to provide an annular pocket for receiving a gasket 92 which forms a part of the running seal between the circular wall 86 and the inner rim of the wheel 30. The self-aligning bearing 68 is suitably mounted in the members 88 and 90 while the shaft 66 projects through the bearing 68 so as to provide a driving connection between the wheel 30 and one of the sections 64 of the rotary brush. By maneuvering the rug nozzle forwardly or reversely over the floor by means of the handle 18 the wheels 30 may be caused to turn, which in turn will through the aforesaid driving connection drive the sections of the rotary brush 60. The gear ratio is such that the peripheral speed of the bristles 62 of the rotary brush may be several times greater than the peripheral speed of the wheels 30.

The circular wall 86 is free to rotate relative to the wheel 30 and the bail 22. The wall members 86 are interconnected by a rod 87. The circular walls 86 associated with each of the wheels 30 along with both sections of the rotary brush 60 are arranged to move together by means of the bracket 80 which is provided with an adjustable connection with the casing 10 so that the rotary brush 60 normally is fixed relative to the mouth 44 of the nozzle and floats therewith relative to the wheels 30.

By the mechanism hereinafter described the bracket 80 is adjustably connected to the casing 10 thereby permitting the position of the rotary brush 60 to be adjusted relative to the mouth 44 of the nozzle to compensate for wear of the bristles 62. As illustrated in Fig. 6, a sleeve 100 projects upwardly from the bracket 80 at the center thereof. A spring 102 surrounding the sleeve 100 is confined between a surface on the hood 14 and a marginal flange on the sleeve 100 for biasing the bracket 80 and rotary brush 60 to its lowermost position relative to the casing. However, a shaft 104 carried by a rotary adjusting member 106 carried by the hood 14 projects down into the sleeve 100 and is provided with oppositely projecting pins 108 which cooperate with oppositely disposed spiral slots 110 formed in the sleeve 100 for locating the bracket 80 relative to the hood 14. By rotating

the adjustable member 106 in a counterclockwise direction from that in which it is illustrated in Fig. 1, the bracket 80 will be moved downwardly relative to the nozzle, while movement of the adjustable member 106 in a clockwise direction from the position in which it is illustrated in Fig. 1 will move the bracket 80 upwardly relative to the nozzle. The adjustable member 106 is adapted to remain in whatever position it is set so as to maintain the adjustment selected.

When the interior of the casing 10 is connected with a source of suction and the rug nozzle is maneuvered over a carpet, a stream of air will enter the mouth 44 of the nozzle carrying with it dirt picked up from the carpet. In addition the rotation of the brush 60 will sweep the surface of the carpet, thereby aiding in removing dirt therefrom. When the rug nozzle is used in connection with a tank cleaner of the type now conventionally used, the suction head at the nozzle 44 will not be very great, but will be sufficient to draw the carpet and particularly the nap thereof opposite the mouth 44 upwardly so as to expedite the cleaning thereof. As previously explained, since the thrust of the handle is taken by the wheels 30, the mouth 44 of the nozzle will ride substantially on the top of the nap of the carpet, irrespective of the character thereof.

While the invention has been described with some detail, it is to be understood that the description is for the purpose of illustration only and is not definitive of the limits of the inventive idea. The right is reserved to make such changes in the details of construction and arrangement of parts as will fall within the purview of the attached claims.

I claim:

1. A cleaning tool comprising a nozzle having a suction chamber formed therein and having an intake mouth formed in a lower wall thereof and communicating with said suction chamber, said lower wall being adapted to be passed over a carpet for cleaning said carpet through said inlet mouth, a pair of wheels disposed in said suction chamber at the opposite ends of said intake, said wheels being adapted to project through said lower wall for engaging said carpet, said wheels being mounted in said casing for movement relative thereto in a direction normal to said carpet, a handle projecting through said nozzle and rotatably supporting said wheels, said handle being mounted in a wall of said nozzle for angular movement relative to said wall and for axial movement of said handle, said handle having a passage formed therein and communicating with said suction chamber for exhausting said chamber during the operation of said tool, a rotary brush in said chamber adapted to project through said intake mouth for engagement with said carpet, bracket means movable with respect to said nozzle for rotatably supporting said rotary brush, adjustable means for supporting said bracket relative to said nozzle, means accessible externally of said nozzle for adjusting said adjustable means for varying the position of said rotary brush relative to said intake mouth, and means responsive to the rotation of said wheels for rotatably driving said rotary brush.

2. A cleaning tool comprising a nozzle having a suction chamber formed therein and having an intake mouth formed in a lower wall thereof and communicating with said suction chamber, said lower wall being adapted to be passed over a car-

pet for cleaning said carpet through said inlet mouth, a pair of wheels disposed in said suction chamber and being adapted to project through said lower wall for engaging said carpet, said wheels being mounted in said casing for movement relative thereto in a direction normal to said carpet, a handle projecting through said nozzle and rotatably supporting said wheels, said handle being mounted in a wall of said nozzle for angular movement relative to said wall and for axial movement of said handle, a rotary brush in said chamber adapted to project through said intake mouth for engagement with said carpet, bracket means movable with respect to said nozzle for rotatably supporting said rotary brush, adjustable means for supporting said bracket relative to said nozzle, means accessible externally of said nozzle for adjusting said adjustable means for varying the position of said rotary brush relative to said intake mouth, and means responsive to the rotation of said wheels for rotatably driving said rotary brush.

3. A cleaning tool comprising a nozzle having a suction chamber formed therein and having an intake mouth formed in a lower wall thereof and communicating with said suction chamber, said lower wall being adapted to be passed over a carpet for cleaning said carpet through said inlet mouth, a pair of wheels disposed in said suction chamber and being adapted to project through said lower wall for engaging said carpet, said wheels being mounted in said casing for movement relative thereto in a direction normal to said carpet, a handle projecting through said nozzle and rotatably supporting said wheels, said handle being mounted in a wall of said nozzle for angular movement relative to said wall and for axial movement of said handle, a rotary brush in said chamber adapted to project through said intake mouth for engagement with said carpet, bracket means supported by and adjustable with respect to said nozzle for rotatably supporting said rotary brush, and means responsive to the rotation of said wheels for rotatably driving said rotary brush.

4. A cleaning tool comprising a nozzle having a suction chamber formed therein and having an intake mouth formed in a lower wall thereof and communicating with said suction chamber, said lower wall being adapted to be passed over a carpet for cleaning said carpet through said inlet mouth, a pair of wheels disposed in said suction chamber and being adapted to project through said lower wall for engaging said carpet, said wheels being mounted in said casing for movement relative thereto in a direction normal to said carpet, a handle projecting through said nozzle and rotatably supporting said wheels, said handle being mounted in a wall of said nozzle for angular movement relative to said wall and for axial movement of said handle, a rotary brush in said chamber adapted to project through said intake mouth for engagement with said carpet, and bracket means adjustable with respect to said nozzle for rotatably supporting said rotary brush.

5. A cleaning tool as defined in claim 4 in which said bracket means extends along the length of said rotary brush and has parallel supports projecting therefrom for rotatably supporting said rotary means at the opposite ends thereof and intermediate said opposite ends.

6. A cleaning tool comprising a nozzle having a suction chamber formed therein and having an intake mouth formed in a lower wall thereof and

communicating with said suction chamber, said lower wall being adapted to be passed over a carpet for cleaning said carpet through said inlet mouth, a pair of wheels disposed in said suction chamber and being adapted to project through said lower wall for engaging said carpet, said wheels being mounted in said casing for movement relative thereto in a direction normal to said carpet, a handle projecting through said nozzle and rotatably supporting said wheels, said handle being mounted in a wall of said nozzle for angular movement relative to said wall and for axial movement of said handle, a rotary brush in said chamber adapted to project through said intake mouth for engagement with said carpet, bracket means adjustable with respect to said nozzle for rotatably supporting said rotary brush, means mounted on said rotary brush responsive to the rotation of said wheels for rotatably driving said rotary brush, and means rotatably mounted about the axis of rotation of said wheels

and movable therewith relative to said nozzle for rotatably supporting said means mounted on said rotary brush.
